Primary Examiner—Mitchell Siegel

Attorney, Agent, or Firm—Skjerven, Morrill, MacPherson, Franklin & Friel LLP

[57] **CLAIM**

The ornamental design for support for partition walls, as shown and described.

DESCRIPTION

FIG. 1 is a perspective view of support for partition walls showing my new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a bottom plan view thereof;

FIG. 8 is a sectional view thereof; and,

FIG. 9 is a perspective view thereof in association with a partition wall and leveling screw that are for illustrative purposes only and form no part of the claimed design.
